DESIGN FOR A CHRISTMAS TREE STAND OR THE LIKE

Clinton T. Evans, Highland Park, Ill., assignor to Montgomery Ward & Co., Incorporated, Chicago, Ill., a corporation of Illinois

Application July 17, 1939, Serial No. 86,056

Term of patent 14 years

To all whom it may concern:

Be it known that I, Clinton T. Evans, a citizen of the United States, residing at Highland Park, in the county of Lake and State of Illinois, have invented a new, original, and ornamental Design for Christmas Tree Stands or the like, of which the following is a specification, reference being had to the accompanying drawing, forming a part thereof.

In the drawing:

I claim:

The ornamental design for a Christmas tree stand or the like, substantially as shown.

CLINTON T. EVANS.
